(57) **CLAIM**

The ornamental design for a fuel transfer pump, as shown and described.

DESCRIPTION

FIG. 1 is a perspective view of a fuel transfer pump showing our new design;

FIG. 2 is a rear-perspective view;

FIG. 3 is an underside-perspective view;

FIG. 4 is another underside-perspective view;

FIG. 5 is a back-elevational view;

FIG. 6 is a front-elevational view;

FIG. 7 is a left-side elevational view;

FIG. 8 is a right-side elevational view;

FIG. 9 is a top view; and,

FIG. 10 is an underside view.

The broken lines in FIGS. 1-10 are included purpose of illustrating environmental matter and forms no part of the claimed design.
